Int. Cl. D11—05

U.S. Cl. D29—1 B

FIG. 1 is a front elevational view of a Christmas ornament showing my new design; and

FIG. 2 is a side elevational view thereof, the side opposite being a mirror image thereof.

The characteristic feature of my design for a Christmas ornament resides in the combination of a nut head having fringe-like whiskers and a peaked hat, all as shown by the drawing.

This is a division of application Ser. No. D. 22,845,

I claim:

The ornamental design for a Christmas ornament, as shown and described.
